United States Patent Office.

HUGH CHRISTIE, OF MORRISANIA, NEW YORK.

Design No. 3,892, dated March 8, 1870.

DESIGN FOR A CARPET-PATTERN.

The Schedule referred to in these Letters Patent and making part of the same.

To all whom it may concern:

Be it known that I, HUGH CHRISTIE, of the town of Morrisania, county of Westchester, State of New York, have invented or produced a new and original Design for a Pattern to be printed upon jute carpeting or other fabrics, in colors similar to those painted on the drawings accompanying this specification, or in other colors substituted in the place of those painted on the drawings herewith; and I do hereby declare that the drawings accompanying this specification do give and convey to any one skilled in the art of manufacturing jute carpeting a thorough description of the nature of my invention, and is sufficient to enable any one skilled in the art of manufacturing jute carpeting to use my invention.

What I claim as my invention, and desire to secure by Letters Patent, is—

The configuration of the design hereunto annexed when made by being wrought upon jute carpeting or other fabrics, in the form similar to the drawings accompanying this specification.

HUGH CHRISTIE.
